(57) **CLAIM**

The ornamental design for a cap of ingredient container, as shown and described.

DESCRIPTION

FIG. 1 is a front perspective view of an ingredient container with the cap;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8. is a bottom perspective view thereof.

The broken lines shown in the figures show features of the cap of ingredient container that form no part of the claimed design.

1 Claim, 8 Drawing Sheets
